United States Patent Office.

CHARLES MERRIAM AND CURTIS O. LUCE, OF BRANDON, VERMONT, ASSIGNORS TO THEM-SELVES AND JULIUS E. HIGGINS, OF SAME PLACE.

Letters Patent No. 75,945, dated March 24, 1868.

IMPROVEMENT IN HAND-STAMPS.

The Schedule referred to in these Letters Patent and making part of the same.

TO ALL WHOM IT MAY CONCERN:

Be it known that we, CHARLES MERRIAM and CURTIS O. LUCE, of Brandon, in the county of Rutland, and State of Vermont, have invented certain new and useful Improvements in Hand-Stamps for post-marking letters, &c.; and we do hereby declare that the following is a full, clear, and exact description of the construction and operation of the same, reference being had to the accompanying drawings, and to the letters of reference marked thereon.

Similar letters of reference refer to corresponding parts in the several figures.

Figure 1 is a side view of the stamp.

Figure 2 is a side view with cap C removed.

Figure 3 is an end view showing the stamp adjusted for making the impression.

Figure 4 is an end view with the cap D removed.

Figure 5 shows the inside of the cap C with the wheel M attached.

Figure 6 shows the cap C without the wheel M; and

Figure 7 shows the inside of one of the annular plates composing the type-wheel A A'.

Figure 8 is the same as the upper part of fig. 2, with the addition of the cap D D and return-cam e e, showing their relative positions.

Our invention relates to that class of hand-stamps in which circular type-wheels are employed, and consists principally in providing a double type-wheel so constructed as to carry a sufficient number of type to represent each day of the month, said type being so constructed as to be readily taken out and replaced, and easily brought into a position to be used.

In combination with this double type-wheel, another single type-wheel is used, having twelve sides, with raised letters to represent each month of the year; and also, in combination with both type-wheels, is a cap with raised letters and figures, showing the name of the post-office and State, with the current year; the whole constituting a cheap, durable, and readily-adjusted hand-stamp for post-marking letters, or for other uses where a stamp is required.

This stamp may be so constructed as to be used as a ribbon-stamp, and may have a cancelling-stamp attached, as shown in fig. 3.

The construction and operation of our invention are as follows: Referring to the drawings, fig. 2 shows the double type-wheel, placed within the case E, to which the band or projection b is attached, for the purpose of holding the type in place. The type-wheel A A' is composed of two annular plates, held together by the rivets r r r. These plates are made with radial grooves on the inside, corresponding with the projections on the type t t t. Inside of the type-wheel A A', and attached to the case D by means of the screw k, is the cam m, by means of which the type, having on its face the number of the day of the month, is raised to its proper position. The type-wheel A A' is turned by a key fitted to the axis P of a pinion working in the annular plate A'. As the wheel A A' is turned, the type t t t are raised by the cam m to the proper position, where they are held, while the stamp is being used, by the spring-catch s, operating on the pinion p'. When it is desired to change the date, the type-wheel is turned till the type that has been in use drops down out of the way, and the next is raised to the level of the face of the stamp ready for use.

For marking the months, we place next to the type-wheel A A' another wheel, M, with twelve sides, upon which are raised letters representing each month in the year. This wheel has a circular projection, i, corresponding to the circular groove o in the cap C, by which it is held in proper position, and has, on its inner edge, cogs for the pinion g. The pinion g has a hollow axis, and fits upon the axis of the pinion p, when the two wheels are put together. The spring-catch w is attached to the cap C, and holds the wheel M in place while being used for stamping. The wheel M is operated by a key fitting upon the arbor of pinion g.

In fig. 4, the two type-wheels are placed, together and put into the case E ready for the cap D, upon which are raised letters and figures representing the post-office, State, and current year. The two figures 67 are placed upon a separate type, made with a shoulder, so as to be removed when it is desired to change the year.

To prevent the type representing the days of the month from falling out while stamping, the strap *e* is inserted in the cap *D*, so as to cover the projection on the side of the type *t t t*.

Having thus described our improvements, what we claim as our invention, and desire to secure by Letters Patent, is—

1. The double type-wheel *A A'*, constructed and operating in combination with the cam *m*, type *t t t*, pinion *p*, and spring-catch *s*, substantially as set forth.
2. The cam *m*, in combination with the return-cam *e*, when used for the purpose described.
3. The arrangement and combination of the type-wheels *A A'*, type-wheel *M*, cap *C*, and case *E*, constructed and arranged substantially as and for the purpose set forth.

CHARLES MERRIAM,
CURTIS O. LUCE.
